UNITED STATES PATENT OFFICE

160,087

ELECTRIC IRON OR SIMILAR ARTICLE

Russell I. Huffman, Dover, Ohio, assignor to
Knapp-Monarch Company, St. Louis, Mo., a
corporation of Delaware

Application November 5, 1949, Serial No. 5,879

Term of patent 14 years

(Cl. D49—6)

To all whom it may concern:

Be it known that I, Russell I. Huffman, a citizen of the United States and a resident of the city of Dover, and county of Tuscarawas, State of Ohio, have invented a new, original, and ornamental Design for an Electric Iron or Similar Article, of which the following is a specification, reference being had to the accompanying drawing, froming a part thereof, in which:

Figure 1 is a perspective view of an electric iron or similar article, showing my new design.

Figure 2 is a top plan view thereof.

Figure 3 is a side elevational view of the iron;

Figure 4 is a front end elevational view thereof; and Figure 5 is a rear end elevational view thereof.

I claim:

The ornamental design for an electric iron or similar article, as shown.

RUSSELL I. HUFFMAN.
